UNITED STATES PATENT OFFICE.

CHARLES CARR, OF BOSTON, MASSACHUSETTS, ASSIGNOR TO JAMES BENNETT FORSYTH, OF SAME PLACE.

DESIGN FOR A MAT.

SPECIFICATION forming part of Design No. 20,107, dated August 26, 1890.

Application filed March 31, 1890. Serial No. 346,085. Term of patent 14 years.

To all whom it may concern:

Be it known that I, CHARLES CARR, of the city of Boston and county of Suffolk, State of Massachusetts, have invented and produced 5 a new and original Design for Mats to be Molded in Rubber, &c., of which the following, together with the illustrative drawings accompanying, is a full description.

The design consists in the illustrated and 10 described shape and ornamentation, including the relative arrangements of the figures of which it is composed.

In the drawings, Figure 1 is a top view or 15 plan. Fig. 2 is a side elevation. Fig. 3 is an end elevation. Fig. 4 is a transverse vertical section.

First, I have a central panel, which is covered with two series of diverse angular lines 20 suitably raised and intersecting each other, so as to form a usual diamond-shaped interstice or pocket between the intersections. This panel or central field of the mat is surrounded by a similar raised line, against which the diagonal raised lines terminate. From 25 this line outward to the edge, and forming an ornamental border extending all around the central field, and limited and inclosed by another raised line forming the extreme outer

edge, is another description of configuration, viz: There are three rows of raised rings or 30 circles extending all around the central field and two rows of half-circles. These circles or rings are intersected by each other and the half-circles in quadrature, as illustrated. A fine variety of individual figures and of composite figures is the result, giving a very pleasing effect. Another feature of the composite configuration is a gradual outward slope given to the top surface of the border configuration, extending from the line inclosing the central 35 field outward to the extreme outer margin of the design. It should not fail to be observed that the quadrate intersections of the raised circles or rings are each common to four of the ring or half-ring members, except at the 40 edges where they join the continuous border line.

I claim—

The design for a mat, consisting, as shown and described, of a central level ornamented 45 field surrounded by a wide outwardly-sloping ornamented margin or border.

CHARLES CARR.
